5 Claims. (Cl. 266—36)

Tilttable, rotating furnaces consisting of a furnace body, rotating in a tilttable frame have found increasing use for metallurgical processes, especially the refining of molten pig iron to steel. The furnace body is then, usually, provided with running or tread rings, supported by rollers in the tilttable frame.

In order that the production may continue without interruption for rebricking of the refractory lining of the furnace, two furnace bodies provided with tread rings are often used with the same rotary stand whereby one is being used while the other one is being rebricked. However, certain difficulties have been encountered because the tread rings must be worn in against the support rollers in order to obtain a quiet operation. The reason for this is that minor differences in the dimensions of the tread rings and their locations on the furnace body are unavoidable.

According to the invention, the furnace body is removably arranged in a rotary, tilttable carrier which can be a ring shaped unit provided with one or more tread (running) rings. In this manner, only the furnace body has to be exchanged while the running rings which are permanently connected with the ring shaped unit do not have to be changed. The ring shaped unit should be provided with suitable devices for centering and fixing the furnace body in the carrier.

The invention will now be further described in connection with certain design examples, shown in the attached drawings.

On the drawings:

FIG. 1 shows diagrammatically a total view of a design in accordance with the invention, seen from the side and with the furnace body lifted up. FIG. 2 and FIG. 3 show a furnace body with different support members in accordance with the invention. FIGS. 4 and 5 show, in longitudinal and cross section, parts of a fastening arrangement in accordance with the invention. FIG. 6 in combination with FIG. 7 shows two longitudinal sections through an alternative design in a holder arrangement with bolt connections and FIGS. 8 and 9 show a further alternative design with a lever attachment.

FIG. 1 shows how the furnace body 1 hanging in wires, chains or lifting yokes, attached to the lifting lugs 2 which are welded to the mouth section of the furnace, may be lifted up or lowered into the ring shaped holder 3 which, with its tread rings 4, is rotatably supported by the support and guide rollers 5 and 6 mounted in bearings 8 which are attached to the tilting frame 9. This frame is tiltably supported by the shafts 11 mounted in the bearing supports 12. In FIG. 1, for the sake of clarity, only some of the supports and guide rollers have been shown which are required in order to carry and guide the ring shaped holder. The tiltability of the frame 9 is indicated by the gear 13. The furnace body 1 can be arbitrarily fixed in the ring unit 3 whereby it must be taken into account that the furnace is subject to considerable thermal expansion both longitudinally and radially. Sometimes, it is advantageous to lift the furnace body with the bottom up which is indicated by the lifting lugs 2, attached to the bottom part of the furnace. If it is desired, the furnace body 1 can be moved into

2

and out of the holder 3 from below which is indicated by the broken line figure towards the bottom of FIG. 1. The furnace body may then be moved with the aid of a platform which can be raised or lowered. The holder 3 with a furnace body 1 attached can be brought into rotating motion with the aid of the motors 14 which are driving one or more of the support and guide rollers 5 and 6. In FIG. 1, the rollers 5 have a supporting function when the furnace is in the horizontal position and the rollers 6 take up the axial load. Which rollers should be driven depends on the position in which it is desired to rotate the furnace body.

In accordance with the invention the furnace body is fixed by a detachable clamping device in the ring shaped frame. This must, firstly, allow a centering of the furnace body and, secondly, permit its thermal expansion as the furnace body usually is fixed in cold condition and thereafter is heated.

In accordance with a preferred embodiment, the furnace body, according to the invention, is provided with circles of supports which cooperate with support or securing devices in the holder. These devices suitably comprise elastic or resilient elements which can take up the thermal expansion of the furnace body. It has proved particularly advantageous to provide one circle of supports with surfaces which form an oblique angle with the longitudinal axis of the furnace body whereby the radial expansion of the furnace body is transformed to an axial slipping which is taken up by the elastic elements in the support or clamping devices.

The attachments may, as is shown in FIGS. 2 and 3, consist of rings 18 and 19, or lugs (pads) 20 and 21. They can also consist of grooves in the furnace body. One of these circles serves to fix the furnace body axially, while the others serve only to support the furnace body and keep it centered but they must permit a sliding in the axial direction during thermal expansion. Both functions may be combined in one and the same circle. In the figures only one circle of each kind has been shown. The ring 19 according to FIG. 2 has an oblique support surface which forms part of a cone. The lugs 21, according to FIG. 3 have oblique side surfaces but may instead be made with an oblique upper surface in the same manner as ring 19.

In the execution shown in FIGS. 4 and 5, the clamping devices consist of a radially adjustable support or clamping jaws 24 and 25 respectively, which can be pressed by screws or wedges against the plane ring 18 and the bevelled ring 19. Correspondingly, the rings may be replaced with lugs in accordance with FIG. 3, that is if the lugs 21 have conical or tapered support surfaces. The furnace body will be centered through these arrangements. The clamping jaws have been provided with guide lugs 27 and 28 respectively which pass through openings in the ring-shaped holder 3. If the clamping jaws are to be pressed in with wedges they are suitably placed in line with the openings 7 in the ring shaped holder. The shoulder ring 19 by having a conical cross section functions as a stop in one direction and at the same time permits axial displacement of the furnace body during its thermal expansion. This displacement takes place against special stops 32 which are fixed in holes 33 in the ring shaped holder 3 and by means of elastic inserts 34, for instance, in the form of resilient inserts such as corrugated steel sheets.

In the case that the supports consist of lugs according to FIG. 3 and one of the circles of lugs is wedge shaped like the lugs 21, the fixing in the axial direction is done by the wedge shaped lugs 21 cooperating with correspondingly shaped supports or clamping devices in the holder 3 which are arranged to register with the interspaces between the lugs 21 and have such form that their oblique

surfaces will come into contact with the corresponding side surfaces of two adjacent lugs 21.

The furnace body 1 may, if desired, be provided with grooves or recesses in which, for instance, wedge shaped clamping lugs may be fitted.

FIG. 6 shows two sections A and B of a different embodiment of the fastening device. The fastening device to the left A is offset on the furnace body in relation to the fastening device to the right B which is shown in FIG. 7. In this manner, it is avoided that the shoulder stops catch when the furnace body is lowered into the ring shaped unit holder. The axial position of the furnace is fixed by the fastening device to the right (FIG. 6). The member 21 is a lug with an oblique surface which rests against the shoulder 35 of the ring shaped unit holder. The contact surface between the lug and the shoulder may be curved or flat. In the former case the common contact surface forms part of the envelope surface of a cone, and in the latter case part of the surface of a pyramid, which later execution may be advantageous because it is easier to machine a flat surface. Furthermore the performance with flat surfaces has the advantage of being more effective in transmitting turning moments. The setting is done according to the execution of FIG. 6 with a wedge shaped block 37 which is placed in between two shoulders 36 and 38 by the bolt joint 39. In order to permit the wedge 37 to be pressed outwardly during the radial expansion of the furnace the bolt joint is suitably provided with an elastic insert, for instance, a cup spring assembly 41 between the wedge and the nut 42. Instead of the large lug 21, also on this side a wedge between two smaller shoulders similar to 38 and 36 can be used whereby the fastening device in FIG. 6B will be symmetrical. The arrangement to the left, FIG. 6A, permits motion in axial direction and shows two wedges 43 and 44 which are tightened in radial direction by an axial bolt joint 39. This is fitted, as shown in the figure, with a wedge 46 instead of a nut which facilitates a more rapid attachment and detachment. The wedges engage oblique shoulders 47 and 48. The contact surfaces between wedges and shoulders are plane, i.e. form parts of a pyramid, which is seen in FIG. 7.

In FIG. 8 another embodiment of the fastening device is shown. The shoulder 19 is a conical ring or wedge formed lug which fits against a conical surface on the ring 51 on the holder or ring shaped unit 3. The furnace is secured to the holder with an angle lever 52 which can be turned around a pin 53 in the ring unit and which presses against the shoulder 19 with a nose 54, and a lever 56 which can be turned around a pin 57 and presses against the circumferential surface on the shoulder or collar 18. Each lever has an arm 58 and 59 respectively which is resilient and fixed to the holder 3 with a bolt 61 and 62 respectively between two ears 63 and 64 respectively. Because the lever is elastic it permits some movement of the shoulder 19 relative to the holder 3. FIG. 9 shows, on a section of a ring unit, how the levers 52 and 56 have been placed between the openings 7 in the unit.

To the left in FIGS. 4, 6 and 8, are shown locking devices which permit movement in axial direction. The shoulder then has its surface parallel with the axis of the furnace body. The clamping blocks 24 in FIG. 4, the wedges in FIG. 6A and the angle lever 56 in FIG. 8 respectively are then used in order to center the furnace body and are not tightened harder than to permit the shoulder to slide in axial direction when the furnace body expands. The thermal expansion in radial direction is

taken up by elastic inserts or the resilience of the lever respectively.

It is, of course, also possible to combine the above described executions for the fastening of the furnace in the ring unit, for instance, to use wedge connections for one circle of shoulder supports and levers for the other. Also, other executions which meet the requirements of rapid fixing and centering of the furnace body and which permits its thermal expansion in axial and radial direction can, of course, be used within the scope of the invention.

What is claimed is:

1. A tiltable rotary furnace which comprises a support; a tilting frame pivotally mounted in said support; a ring-shaped holder; at least one ring-member, including at least one tread ring, exteriorly secured to said ring-shaped holder; support and guide rollers and at least one drive member, rotatably mounted in said tilting frame, said drive member engaging said ring-member; said ring-shaped holder being supported on and guided by said support and guide rollers and rotated by said drive member; a furnace body adapted to be encircled by said ring-shaped holder; and a securing means, carried on said ring-shaped holder, for centering said furnace body within, and detachably securing said furnace body in, said ring-shaped holder.
2. The rotary furnace defined in claim 1, in which said ring-member includes a cog-ring and in which said drive member includes a pinion cooperating with said cog-ring.
3. A tiltable rotary furnace as defined in claim 1, wherein said securing means includes shoulder members, carried on said furnace body, cooperating with fastening members carried in said ring-shaped holder.
4. A tiltable rotary furnace as defined in claim 1, wherein said securing means includes at least one shoulder member, carried on said furnace body, cooperating with fastening members carried in said ring-shaped holder, said member having a bearing surface which forms an oblique angle to the longitudinal axis of the furnace body, said fastening members comprising engagement members having surfaces complementary to and adapted to engage said bearing surface on said shoulder member.

5. A tiltable rotary furnace as defined in claim 4, wherein said fastening members comprise stop members attached to said ring-shaped holder and arranged to prevent substantial movement of said shoulder member relative to said engagement members axially of said furnace body along said bearing surface and wherein said stop members include elastic or resilient elements which provide for such limited relative movement for accommodation for thermal expansion and contraction of said furnace body within said ring-shaped holder.
